CAPPING MACHINE

Hugh Mair, Cranford, N. J., assignor to The Distillers Company Limited, Linden, N. J., a corporation of Delaware

Application March 23, 1944, Serial No. 527,683

7 Claims. (Cl. 226—81)

This invention relates to improvements in bottle capping machines, the principal object of the invention being to provide a machine of this character in which the capping operation is automatically controlled by electrical means the actuation of which is initiated by the container as it passes into position to be sealed.

A further object of the invention is to provide a machine specially adapted for sealing containers having lever-type closures, the machine being equipped with automatically operative lever-actuating mechanism.

A further object of the invention is to simplify the general construction of a machine of the character set forth and at the same time to provide a machine which is time-saving and economical in operation and of maximum productive capacity.

Other objects and advantages of the invention will appear as the description proceeds.

In the drawings accompanying this specification,

Fig. 1 is a front elevation of a machine constructed in accordance with the present invention.

Fig. 2 is a side elevation of the machine shown in Fig. 1.

Fig. 3 is a side elevation showing on a larger scale the mechanism shown in Fig. 2 and also showing a container in the capping position ready for the cap compressing operation.

Figs. 4 and 5 are sectional plan views taken on the lines 4—4 and 5—5 respectively of Fig. 3, looking in the direction indicated by the arrows.

Fig. 6 is a front view of the machine showing a completely capped bottle at one side of the capping platform and an uncapped bottle at the opposite side thereof.

Fig. 7 is a rear elevation of the machine showing the plunger armature of the solenoid in the idle position.

Fig. 8 is a side view similar to Fig. 3 but showing the capping and lever-clamping operation completed; and

Fig. 9 is a diagrammatic view of the wiring system.

The same reference characters designate the same parts in the different figures of the drawings.

Referring now in detail to the drawings, 1 designates the upright standards and 2 the stays or brace members constituting the frame of the machine, while the transverse members of the frame are designated 3. At the top of the frame is supported a hopper 4 for the reception of bottle caps,

the lower end of said hopper being in communication with a chute 5 the delivery end of which is disposed in position to deliver one cap to each bottle as the latter is passing into position to be capped.

In front of the machine frame are disposed a pair of endless conveyor belts 6 and 7 traveling on pulleys or rollers 8 and 9 respectively mounted for rotation on stud shafts 10 and 11 supported in two of the upright machine frame members. The conveyor belt 6 carries the filled bottles into position to be capped and the belt 7 receives the bottles after the capping operation has been completed and carries them away to be packed for shipment. For this purpose the pulleys 8 and 9 are spaced apart a sufficient distance to permit a work table 12 to be secured on the machine frame between the belts with the top surface of the table in the same horizontal plane as the top surfaces of the belts, the opposite sides of the table being bevelled below so as to permit them to partially overlie the pulleys 8 and 9. The belts are maintained in horizontal position by pairs of L-shaped supporting members 13 bolted to the machine frame at opposite sides of the pulleys 8 and 9. At a suitable distance above the work table 12, depending on the height of the bottle to be capped, an L-shaped guide bar 14 is secured to the frame of the machine, along the side edge of which bar the necks of the bottles are guided during their passage to and from the work table.

The capping mechanism proper will now be described:

At some distance above the work table 12 a top plate 15 (Figs. 3 and 8) is secured to the uprights of the machine frame and projects out over the work table, said plate having an opening in which is mounted for vertical sliding movement a spindle or stem 16 carrying at its lower end a capping head 17 in vertical alignment with the center of the work table 12. The stem 16 carries a plurality of weights 18 resting on the capping head whereby the latter is normally urged toward its lowermost position. For moving the capping head and its weights upward a lever formed of two bars 19 fulcrumed at 20 on a bracket carried by the machine frame is pivoted at its front end to the capping head, as shown at 21, said lever being extended rearwardly through the machine frame. On the rear of the machine frame at the upper part thereof is bolted a solenoid 22 having a depending plunger 23 provided with a slot 24 through which passes a pin 25 to which are secured the rearmost ends of the lever bars 19, at opposite sides of the plunger as shown in Figs. 5

and 7. Below the slot 24 the plunger is shaped to form a disc 26 and below said disc extends a rod or stem 27 which passes through an opening in a plate 28 secured to the machine frame. A counterweight 29 is mounted on said rod below the plate 28, so that the vertical movement of the solenoid plunger is limited by the contact of the disc 26 and the counterweight 29 respectively with the plate 28. The weight of the plunger and its counterweight 29 exerting pressure on the end of the lever 19 through the pin and slot connection 24, 25 is sufficient normally to overbalance the capping head 17 and its weights 18 and thereby maintain them in the uppermost position as best shown in Fig. 3.

Mounted for sliding movement from front to rear of the machine frame is a slide-bar 30 having at its forward end a cam nose 31 that normally extends out beyond the guide bar 14 into the path of the tops or necks of the bottles as they pass on to the platform 12 (see Fig. 4) to have a cap compressed on the successive bottles. The slide-bar 30 is normally retained in the forward position by the tension of a spring 32 secured at one end to the machine frame and at its opposite end to a stud or lug 33 secured in the slide bar at its underside (see Figs. 3 and 8). Near its rear end the slide bar 30 has formed on its underside a thickened or block portion 34 adapted to engage a horizontally disposed lever 35 pivoted at 36 (Figs. 4 and 5) on one of the transverse frame members of the machine. The said lever 35 carries at its further end an adjustable contact pin 37 adapted when the lever is swung in one direction to engage and operate a micro-switch 38 into circuit closing position. At its opposite end the lever 35 is provided with a second adjustable pin 39 for limiting the swinging movement of the lever. Supported at any convenient point on the machine frame is a magnetic switch 40 of any well-known conventional type, the purpose of which will appear as the description proceeds.

Referring now to the wiring diagram shown in Fig. 9, the micro-switch 38 is connected by wires 41 and 42 directly through main line wires 43 and 44 with a suitable source of current (not shown), the said main line wires being also connected to terminals 45 and 46 of the magnetic switch 40. Two opposite terminals 47 and 48 of the magnetic switch are connected by wires 49 and 50 with the solenoid 22. The magnetic switch is provided with the usual magnetic coil indicated at 51 and circuit closing elements 52 and 53 for bridging the gaps between terminals 45-47 and 46-48. With this arrangement it will be obvious that when the micro-switch 38 is operated into circuit-closing position current will flow therethrough and through the coil 51 of the magnetic switch thereby energizing said coil and causing the elements 52, 53 to swing into circuit-closing position so that current will now flow directly through the solenoid 22, thus energizing the same and causing its plunger armature 23 to rise with a quick movement, thus permitting descent of the capping pressure head 17 under pressure of the weights 18.

Returning now to the mechanical operation of the machine it is to be understood that the conveyor 6 will be loaded with a continuous succession of filled bottles placed side by side on the conveyor and as the conveyor travels the foremost bottle (as for instance the bottle shown at the left in Fig. 6) will be pushed on to the table 12 by the succeeding bottles. As each bottle

passes from the conveyor 6 on to the table 12 the neck of the bottle engages the cam nose 31 of slide bar 30 and pushes the latter back so that its block 34 engages the lever 35 and swings said lever on its pivot thereby setting the micro-switch 38 in circuit-closing position and initiating the operation of the magnetic switch 40 and solenoid 22 as above described.

The pressure head 17 has formed thereon a pair of slotted ears 55 between which is guided a depending tongue 56 pivoted at 57 to the lower end of a link 58 which itself is pivoted at 59 between the front ends of bars 60 forming a lever fulcrumed at 61 on the machine frame, the rearward ends of said bars being also pivoted to a block 62 from which depends a stem 63 which is guided through an opening in a bracket 64 secured to the plunger 23 of the solenoid 22. The stem 63 is provided with a head 65 at its lower end for limiting the movement of said block with relation to the bracket 64. The slots in the ears 55 are in the nature of cam slots and the depending tongue 56 is provided with a pair of pintles or guide pins 66, one at each side of said tongue, traversing said slots, as does also the pivot 57, so that during the operation of the lever 60, the tongue 56 is moved from the position shown in Fig. 3 to the position shown in Fig. 8, during which movement it has shifted the bottle-cap-lever to the clamping position shown in said Fig. 8.

It is believed that the operation of the machine will be clear from the foregoing description. As each successive bottle on the conveyor 6 arrives at the position shown in Fig. 6—that is to say, approximately half of the diameter of the bottle being over the work table 12—the top of the bottle passing below the lower end of the cap chute engages the lowermost cap in said chute and carries it along with the bottle to the capping position centrally of the work table. During its passage to said capping position the neck of the bottle engages the cam nose 31 of the slide bar 30 (Figs. 3, 4 and 8) and pushes said bar toward the rear. During its rearward movement the slide bar 30, by means of its block portion 34, swings the lever 35 on its pivot, thereby causing said lever to actuate the micro-switch 38 into circuit-closing position, whereupon the magnetic switch 40 and solenoid 22 are brought into operation as already described in connection with Fig. 9. The plunger 23 of the solenoid 22 rises suddenly, thus releasing the lever 19 so that the forward end of said lever and the capping head 17 attached thereto are moved downward under pressure of the weights 18, thus compressing the cap on the mouth of the bottle. In the meantime, during the upward movement of the solenoid plunger 23, the bracket 64 carried by said plunger has engaged the block 62 to which the rear end of lever 60 is pivoted and moved said block upward to the position shown in Fig. 8, so that the depending tongue 56 at the forward end of said lever has engaged and swung the cap-lever into clamping position on the bottle, thus completing the capping and clamping operation. During the upward movement of the plunger 23, its disc 26 has also engaged the rear end of the slide bar 30 and raised it so that its block portion 34 releases the lever 35 and permits the latter to swing under tension of its spring 54 so as to disengage the micro-switch 38 and permit the latter to return to its normal open-circuit position, the slide bar 30 having in the meantime been caused to slide forward un-

der tension of its spring 32 thereby carrying the cam nose 34 of the slide bar into position to be engaged by the next succeeding bottle on the conveyor 6.

It will be understood that all of the operations above described occur within the infinitesimal period of time required for the movement of the foremost bottle on the conveyor 6 into capping position on the work table, said movement being caused by the pushing effect of the succeeding bottles on the conveyor 6, which pushing effect continues to exert itself on the capped bottles until they are successively moved from the work table 12 on to the discharge conveyor 7.

Having thus described my invention, what I claim as new and desire to secure by Letters Patent is:

1. In a capping machine, a container-support, a vertically reciprocable capping head above said support, pressure means for moving said head toward the container-support, means including a member movably connected with the head and effective against the action of said pressure means to maintain the head in uppermost position, an electromagnet having an armature associated with said movable member for moving the same thereby to release the head for movement to capping position under the action of said pressure means, a container-actuated trip to energize said electromagnet, and means actuated by movement of the head in capping direction to deenergize the electromagnet.

2. In a capping machine, a container-support, a vertically reciprocable capping head above said support, weights associated with said head and effective to move the same toward the container-support, means including a weight movably connected with the head and effective against the action of said first weights to maintain the head in uppermost position, an electromagnet having an armature associated with said movable weight for moving the same thereby to release the head for movement to capping position under the action of said first weights, a container-actuated trip to energize said electromagnet, and means actuated by movement of the head in capping direction to deenergize the electromagnet.

3. In a capping machine, a container-support, a capping head mounted for vertical reciprocation above said support, pressure means associated with said head for moving it toward the container-support, a fulcrumed lever pivoted at

one end to said capping head, movable means acting on the opposite end of the lever to depress the same thereby to maintain the capping head in uppermost position against the action of said pressure means, an electromagnet having an armature associated with said movable means for moving the same away from said lever thereby to release the head for movement to capping position under the action of said pressure means, 10 a container-actuated trip to energize said electromagnet, and means actuated by movement of the head in capping direction to deenergize the electromagnet.

4. In a capping machine, a container-support, a capping head mounted for vertical reciprocation above said support, pressure means associated with said head for moving it toward the container-support, a fulcrumed lever pivoted at one end to said capping head, an electromagnet 15 having a weighted armature acting on the opposite end of said lever to depress the same thereby to maintain the capping head in uppermost position against the action of said pressure means, said armature being movable relatively to the lever thereby to release the head for movement to capping position under the action of said pressure means, a container-actuated trip to energize said electromagnet, and means actuated by movement of the head in capping direction to deenergize the electromagnet.

5. In a capping machine as set forth in claim 1, means carried by the capping head and actuated by the movement of said armature for swinging the lever of a lever-type cap into clamping position on arrival of the capping head at capping position.

6. In a capping machine as set forth in claim 1, means carried by the capping head to engage and swing the lever of a lever-type cap into clamping position, a fulcrumed lever pivoted to said cap-lever engaging means, and cooperating means carried by said lever and armature for actuating said cap-lever engaging means on arrival of the capping head at capping position.

7. In a capping machine as set forth in claim 1, the container-actuated trip comprising a slideable member having a cam portion projecting into the path of a container, said member being slideable by the container as it passes on to said container-support and a micro-switch actuated by said slideable member to close a circuit through said electromagnet.

HUGH MAIR.
